UNITED STATES PATENT OFFICE.

EDWARD L. CALEY, OF PHILADELPHIA, ASSIGNOR TO GEORGE W. FLOYD, IRVIN I. WELLS, ISAAC BROOKE, CHRISTIAN W. WAGNER, WILLIAM WAGNER, ISAAC HALLMAN, AND DAVID FINKBINER, ALL OF ROYER'S FORD, PENNSYLVANIA.

DESIGN FOR A CHAMBER-CASING FOR STOVES.

SPECIFICATION forming part of Design No. 16,815, dated July 20, 1886.

Application filed May 20, 1885. Serial No. 168,178. Term of patent 7 years.

To all whom it may concern:

Be it known that I, EDWARD L. CALEY, a citizen of the United States, and a resident of Philadelphia, Pennsylvania, have invented a new and original Design for a Heating-Stove Casing, of which the following is a specification.

My design is shown in the accompanying illustration.
10 The design relates only to the casing A, which surrounds the air-heating chamber of the stove; and the novelty of the design consists, mainly, in the concave shape of said casing, whereby a more attractive appearance 15 than that presented by the usual straight casing is imparted to this portion of the stove. The casing is separated by bands B into a series of panels, each of which has a central medallion, D, and is further ornamented by

line-work of a character too fully shown to 20 need description.

The configuration and ornamentation of the other parts of the stove form no part of my design.

I claim—
25 The design for the air-chamber casing of a heating-stove, said design consisting of the concave casing separated into panels by bands B, each panel having a central medallion and subordinate ornamentation, as shown and described.

In testimony whereof I have signed my name to this specification in the presence of two subscribing witnesses.

EDW. L. CALEY.
